Specification of Letters Patent. Patented June 8, 1915.

Application filed July 30, 1913. Serial No. 781,980.

To all whom it may concern:

Be it known that I, FELIX E. VALOIS, a citizen of the United States, residing at Haverhill, county of Essex, State of Massachusetts, have invented a certain new and useful Improvement in Seams, of which the following is a specification, reference being had therein to the accompanying drawings.

My invention has for its object a new and improved seam for boots and shoes, harness and the like. In the following specification and in the accompanying drawings I have shown my novel seam as applied to boots and shoes and harness.

The particular object of the invention is to provide a method of interlocking the stitches composing the seam such that the two or more thicknesses of material will be held together firmly even after the material has worn down so much as to cut off the ends or loops of the stitches; also to give the seam greater and more uniform strength and flexibility.

Heretofore in sewing the soles of shoes to the welt, the depth of the so-called "lock" in the stitches, *i. e.* the point at which the two threads cross or loop through each other, has been the same for each stitch. It has resulted that the ends or loops of the stitches on the bottom of the sole have worn off as the sole has worn away and the stitches have then been held only by frictional engagement and have pulled out of the holes in the sole, thus allowing the sole to separate from the welt. I have accordingly invented a novel seam which remedies this defect. The seam embodying my invention has the locks of the stitches composing the seam located at different depths in the layer of material. In practice, I find it convenient to alternate the stitches, but this is not necessary and I do not limit myself to this arrangement as it is sufficient to arrange the locks of succeeding stitches at different depths. The result of this arrangement is that the sole and welt will not pull apart until the sole has worn away sufficiently to destroy the lock, since, as is well known, a stitch will not ordinarily pull out so long as the lock is intact. If desired, the locks of some of the stitches may be located in one layer of material, while other stitches are in other layers and this gives additional flexibility to the seam and strength to the

article, because the locks of adjacent stitches 55 not being side by side, the leather between the stitches is not crowded together at this point and thereby rendered weaker and stiffer. The change in the position of the locks also tends to make the work lie flat and 60 prevents curling.

The seam may be easily produced by a simple change in the thread measuring device of the sewing machine so that the thread measured off for certain stitches will be 65 longer than that for others.

The invention will be fully understood from the following description taken in connection with the drawings, and the novel features are pointed out and clearly defined 70 in the claims at the close of this specification.

In the drawings, Figure 1 is a section of a seam embodying my invention, the parts being enlarged and somewhat exaggerated for 75 convenience of illustration. Fig. 2 shows the seam shown in Fig. 1 with a portion of the sole worn away. Fig. 3 shows another form of seam. Fig. 4 shows the seam applied to a shoe having a double sole. 80

Referring to the drawings, and particularly to Fig. 1, at A is shown one layer and at B another layer of material to be united by a seam. For convenience, the layer A may be considered to be the welt of a shoe 85 and the layer B the sole. At C is shown one thread and at D another thread, said two threads being interlocked to form the seam. The thread C enters on the welt side and the thread D on the sole side of the material. 90 The thread C passes down through the welt A and into and part way through the sole to a point where it engages the other thread D. It passes around the thread D forming the lock 1 and then back through the hole, along 95 the surface of the welt and then all the way back through the welt and part way through the sole forming the lock 2. It will be seen that the lock 1 is close to the top surface of the sole while the lock 2 is near the bottom 100 of sole and that the locks of the succeeding stitches alternate, one set of locks being close to the top of the sole and the other set being close to the bottom of the sole.

I have shown a simple form of stitch, but 105 it will be understood that I do not limit myself to this stitch since any stitch may be employed in which the locks may be located

at different depths in the material. This is accomplished by measuring off different lengths of thread for the stitches having locks at different depths. The different depths of the locks may alternate or may be interspersed irregularly.

As the shoe wears, the loops 4 of the bottom thread first wear off; then, as the sole wears down more, the locks 2 which are near 10 the bottom of the sole wear off, but the sole and welt are still held together firmly because the stitching cannot pull out as long as the locks 1 which are near the welt are intact. This is illustrated in Fig. 2 where 15 the sole is shown worn away so that the locks 2 have been destroyed, but the layers of leather are still held together.

In Fig. 3, there is illustrated another seam embodying my invention. In this seam, 20 certain of the locks, these being numbered 5, are in the bottom layer of material near to the lower surface of the upper layer, while others of the locks, these being designated 6, are in the upper layer of material. 25 This seam is very flexible and is also particularly adapted for use in harness because the leather between the locks of two adjacent stitches is not crowded together as is the case when the locks are all on the same level.

30 In Fig. 4, I have shown a section of a shoe having a double sole. The welt is designated E, the intermediate layer F; and the outsole G. The locks 7, 7 of certain of the stitches are located in the outsole G near its

top surface, while the locks 8, 8 of other 35 stitches are located in the intermediate layer.

What I claim is:

1. In combination with a plurality of layers of material, a series of stitches uniting them together, said stitches having locks 40 which vary in depth in regular predetermined sequence and which have regular and predetermined variations in depth.

2. In combination with a plurality of layers of material, a series of stitches uniting them together, said stitches having locks 45 which vary in depth in regular predetermined sequence and which have regular and predetermined variations in depth, some of said locks being located in predetermined 50 order of arrangement nearer the outer surface of one of the layers of material which are united by the seam and others of said locks being located in predetermined order of arrangement nearer the contiguous surfaces of two of the layers.

3. In combination with a plurality of layers of material, a seam having locks which vary in depth in regular predetermined sequence and have regular and predetermined variations in depth, the stitches of varying depths being drawn equally taut.

In testimony whereof I affix my signature, in presence of two witnesses.

FELIX E. VALOIS.
